(57) **CLAIM**

The ornamental design for a dual opening electronic cigarette e-liquid bottle, as shown and described.

DESCRIPTION

FIG. 1 is a perspective view of the dual opening electronic cigarette e-liquid bottle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional view taken along line 8-8 of FIG. 4.

The broken lines in the drawings depict portions of the dual opening electronic cigarette e-liquid bottle that form no part of the claimed design.
